UNITED STATES PATENT OFFICE.

THOMAS L. DENNIS, OF NEW YORK, N. Y., ASSIGNOR TO GEORGE F. PARKER, OF NEW YORK, N. Y.

CURLING-IRON.

1,388,805.

Specification of Letters Patent. Patented Aug. 23, 1921.

Application filed August 18, 1920. Serial No. 404,456.

To all whom it may concern:

Be it known that I, THOMAS L. DENNIS, a citizen of the United States, and resident of the city of New York, Prince Bay, borough 5 of Richmond, in the county of Richmond and State of New York, have invented a new and Improved Curling-Iron, of which the following is a full, clear, and exact description.

10 This invention relates to curling irons and particularly to improved electrically heated curling irons and has for an object to provide an improved construction wherein the heating medium is so positioned as to produce the desired heating results without interfering with the movable parts of the iron.

Another object is to provide an improved construction having a suitable shaped handle formed with a notch or socket for receiving 20 the end of the retaining member when pressed, the structure being such that the movement of the thumb in operating the device is comparatively short.

A still further object of the invention is 25 to provide an electrically heated curling iron provided with a hair retaining member so pivoted that the thumb is raised only a minimum distance from the handle when actuating the same, and to offer as little 30 obstruction as possible in curling.

In the accompanying drawing:—

Figure 1 is a longitudinal vertical section of an improved curling iron disclosing an embodiment of the invention, the same being 35 taken approximately on line 1—1 of Fig. 2.

Fig. 2 is a top plan view of the curling iron shown in Fig. 1.

Fig. 3 is a transverse sectional view through Fig. 1, on line 3—3.

40 Referring to the accompanying drawing by numerals 1 indicates the heating tube which is closed at the outer end 2 but open at the inner end 3 so as to admit the electric supply wires 4 to the heating element 5.

45 The heating element 5 may be of any desired construction and the supply wires 4 may be connected to a suitable source of electrical supply by any suitable coupling members 6. As shown in the drawings, the cou-

50 pling members 6 are carried by a block 7 fitted into a recess in the handle 8 and held therein by suitable screws 9. The handle 8 is hollow and is shown as tapering from where it receives the tube 1 to the outer end 55 carrying block 7, though if desired it could

be made of different shapes without departing from the spirit of the invention. The handle is also shown hollow though this is not essential but preferable as it produces a lighter construction and at the same time 60 provides an easy passage-way for the wires 4 and an opening for receiving the end 10 of the retaining member 11. In order that the end 10 may move pivotally into the handle 8, the notch or slot 12 is provided 65 therein and extends to the clamping ring 13. This clamping ring is provided with upwardly extending ears 14 and 15 for accommodating the pivotal pin 16 which extends on through the flanges 17 and 18 of 70 the retaining member 11.

A spring 19 is carried by the pin 16 and bears against end 10 and against part of the shoulder 20 so as to continually urge the end 10 to an outer position as shown in Fig. 1, 75 which position causes the clamping end 21 to press against the tube 1 or against any hair placed thereon.

From Fig. 1 it will be observed that the member 11 is curved upwardly at 22 and at 80 approximately the center of this upward bend or groove the pin or pintle 16 is placed whereby the end 10 is substantially flush with the outer surface of handle 8 while the gripping portion 21 is engaging the tube 1. 85

When it is desired to use the curling iron the person may easily grasp the handle 8 and arise the thumb only a short distance so as to rest on top of the thumb member 23 which is pressed and by said pressure causes 90 the end 10 to be depressed and the clamping end 21 to be elevated. If the movement is continued to its fullest extent part of end 10 will eventually rest against the shoulder 20. The wires 4 are arranged preferably at one 95 side or near the bottom of handle 8 so that they will not interfere with the end 10 in its downward movement.

What I claim is:—

1. A curling iron comprising a heating 100 bar, a handle carrying said heating bar and formed with a notch therein, a hair retaining member pivotally carried by said handle, the pivotal mounting of said retaining member being placed a short distance from 105 one end, and means for depressing one end of the retaining member into said notch for elevating the opposite end.

2. A curling iron comprising a heating member, a hollow handle connected with the 110

said heating member, said handle having a notch therein adjacent the end carrying the heating member, a retaining member having a depressible end and a clamping end, means for pivotally mounting said retaining member on said handle, and a thumb member mounted on the depressible end, said thumb member being elongated in a direction perpendicular to the depression end whereby when said thumb member is pushed toward the handle, said depressible end will be moved into said handle and the clamping end moved away from said heating member.

3. A curling iron comprising a hollow handle provided with a notch adjacent one end, a heating member extending into said handle, a ring member surrounding one end of said handle, said ring member being provided with a pair of spaced ears, a hair retaining member substantially U-shaped in cross section extending between said ears, a pivotal pin extending from said ears through the flanges of said hair retaining member, a spring acting on said hair retaining member for holding the same in a certain position and a thumb member connected with one end of said retaining member and per-

pendicular thereto positioned to force one end of said retaining member into said notch and move the opposite end of the retaining member in a direction away from said heating member.

4. A curling iron comprising a hollow heating member, a heating element arranged in said heating member, means for supplying electrical energy to said heating element for producing heat therein, a handle surrounding one end of said heating member, said handle being formed with a slot adjacent said last-mentioned end and with a shoulder adjacent the end of the heating member, a ring member surrounding said last-mentioned end of said handle, a hair retaining member formed with a bowed section intermediate its ends, means for pivotally mounting said bowed section onto said ring member, and a thumb member connected to one end of said retaining member, said thumb member and the end of the retaining member to which it is connected being capable of pivotal movement through said slot into said handle until the last-mentioned end engages said shoulder.

THOMAS L. DENNIS.
